TOY MODEL CAR

George Barris, North Hollywood, Calif., assignor to
Zee Toys, Inc.

Original design application Dec. 18, 1972, Ser. No.
316,411, now Patent No. 230,178, dated Jan. 29,
1974. Divided and this application Jan. 22, 1974,
Ser. No. 435,597

Term of patent 14 years

Int. Cl. D21—01

U.S. Cl. D34—15 AN

FIG. 1 is a perspective view of a toy model car showing my new design;

FIG. 2 is a rear elevational view thereof;

FIG. 3 is a side elevational view thereof, from the side opposite the side shown in FIG. 1;

FIG. 4 is a bottom plan view thereof; and

FIG. 5 is a front elevational view thereof.

This is a division of design application Ser. No. 316,411, filed Dec. 18, 1972, now Pat. No. D. 230,178, issued Jan. 29, 1974.

I claim:

The ornamental design for a toy model car, as shown and described.
